UNITED STATES PATENT OFFICE.

ROBERT THOMAS MULLINS, OF BROOKLYN, NEW YORK, ASSIGNOR TO A. G. SPALDING & BROS., OF NEW YORK, N. Y., A CORPORATION OF NEW JERSEY.

FOOTBALL HELMET.

Application filed February 15, 1927. Serial No. 168,254.

The present invention relates to the type of helmets adapted particularly for use in games such as football, soccer, etc., and more particularly deals with the improved forms of such helmets wherein chin straps have been dispensed with.

An object of the invention is to provide a helmet which fits the head snugly and has an adjustable pad which engages the lower part of the rear of the head just above the nape of the neck. Although pads have previously been used in connection with helmets of various kinds the present construction is designed so that the pressure between the forehead and the rear portion of the head will be distributed over a sufficient area to render the head piece quite comfortable and prevent the dislodging thereof during play. The specific construction of the pad used herein causes the entire inner surface of the helmet to conform very closely to the player's head and the means for adjusting the pad is concealed between the pad and the outer portion of the helmet so that the continuity of the outer surface is unbroken.

The present invention relates to an improved form of helmet embodying the features described above and provides an additional means for causing the helmet to fit the player's head snugly, and yet to provide a certain degree of adjustability both with respect to the size of the head upon which it is to be used, and the gripping force upon the head.

Reference will now be had to the accompanying drawings forming a part hereof for a more detailed description of the invention, wherein:

Figure 1 is a front elevation of a proposed form of the invention.

Figure 2 is a section taken on line 2—2 of Figure 3, and showing the adjustable feature of this invention.

Figure 3 is a section taken on line 3—3 of Figure 2, and showing the manner in which the elements have been assembled to facilitate the adjusting of the size of the helmet.

In the drawings *a* designates the upper or crown portion of the helmet, and *b* designates the lower portion which is secured to the crown portion by means of suitable straps *a'*. Ear extensions *b'* are provided in the usual manner and a suitable felt lining *b''* is applied to the inner surface of the

helmet to provide the necessary cushioning function.

At the rear of the lower portion *b*, a leather section *c* is provided which does not have the felt lining *b''*. Sewed at the top of this leather portion *c*, is a flap *d*, it being secured to the portion *c* by means of suitable stitching *d'*. This flap has on its inner side, felt padding *b''* similar to that described previously.

In the form of the invention disclosed herein the leather flap *d* is provided with two slits *d''* at either end of the flap, the purpose of this appearing later. At either side of the leather portion *c*, vertical tabs *e* are provided and are stitched as at *e'* to the ear extensions *b'* of the helmet. These tabs are provided with slits *e''* adapted to receive an elastic band *f*, the tension of which varies the effective size of the helmet. The band *f* extends beneath the flap *d* and the felt portion *b''* thereof, and passes through the slits *e''*. The two ends *f'* of this strap *f* pass through the slits *d''* in the flap *d*, and have formed therein eyelets *f''* which are adapted to receive a lacing *g*.

It will be evident that the lacing may be secured in a manner to set up a desired degree of tension in the elastic band, and the flap *d* will be forced outwardly against the player's head to a corresponding extent. Setting up a tension in the flexible strap and forcing the flap outwardly is accompanied by a constriction of the lower portion *b* of the helmet about the side of the head and in this manner the head not only receives the direct force of the pad at the rear, but also has the gripping force of the side portions applied thereto and as a result, a very uniform adjustability is provided. The manner in which these elements have been illustrated herein has been found to be particularly desirable, and the adjusting of the tension of the strap has been facilitated by this specific construction. It will be noted that the elements have been effectively concealed beneath the leather portions *c* so that none of them is exposed, and the adjustable members may be easily removed and replaced.

A vertical re-enforcing strap *a''* may be applied and the successive layers may be secured in position by suitable stitching *a''*.

It will be evident that the invention may

be embodied in many different forms, the arrangement of the elements as shown herein merely serving to illustrate one specific modification. Although only this modification has been shown and described herein, the invention is not to be limited save as defined in the appended claims.

What I claim is:

1. In a football helmet having a crown and a lower section of leather, a flap, and means to secure the flap adjustably within the lower section of the helmet comprising, a strap, and means to vary the effective length of the strap, whereby the helmet may be adjusted to the head of the wearer, the outside of the lower section of the helmet being unbroken and all said elements lying inside said lower section.

2. In a football helmet having a crown and a lower section of leather, a flap, and means to secure the flap adjustably within the lower section of the helmet comprising, a strap, and means to vary the effective length of the strap co-operating with the ends of the strap and located between the flap and the inside of the lower section of the helmet, whereby the helmet may be adjusted to the head of the wearer.

3. In a football helmet having a crown and a lower section of leather, a flap, and means to secure the flap adjustably within and at the rear of the lower section of the helmet comprising, tabs secured to the said lower section, a strap co-operating with the tabs and with the flap, and means to vary the effective length of the strap, whereby the helmet may be adjusted to the head of the wearer, the outside of the lower section of the helmet being unbroken and all said elements lying inside said lower section.

4. In a football helmet having a crown and a lower section of leather, a flap, and means to secure the flap adjustably within

and at the rear of the lower section of the helmet comprising, tabs secured to the said lower section, a strap co-operating with the tabs and with the flap, and means to vary the effective length of the strap co-operating with the ends of the strap and located between the flap and the inside of the lower section of the helmet, whereby the helmet may be adjusted to the head of the wearer.

5. In a football helmet having a crown and a lower section of leather, a flap, slits in the flap, and means to secure the flap adjustably within and at the rear of the lower section of the helmet comprising, tabs secured to the said lower section, slits in said tabs, a strap passing through the slits in the tabs and the slits in the flap, and means to vary the effective length of the strap co-operating with the ends of the strap and located between the flap and the inside of the lower section of the helmet, whereby the helmet may be adjusted to the head of the wearer.

6. In a football helmet having a crown and a lower section of leather, a flap, slits in the flap, and means to secure the flap adjustably within and at the rear of the lower section of the helmet comprising, tabs secured to the said lower section, slits in said tabs, a strap passing through the slits in the tabs and the slits in the flap, means to vary the effective length of the strap co-operating with the ends of the strap and located between the flap and the inside of the lower section of the helmet, whereby the helmet may be adjusted to the head of the wearer, and a pad secured to the inner side of the flap to cushion it against the head of the wearer.

This specification signed this 11th day of February A. D. 1927.

ROBERT THOMAS MULLINS.
